JOSEPH C. TONE AND HENRY A. CLUM, OF ROCHESTER, NEW YORK, ASSIGNEES TO
THEOBALD W. TONE, OF SAME PLACE.

Letters Patent No. 96,508, dated November 2, 1869.

IMPROVEMENT IN HAND-STAMPS.

The Schedule referred to in these Letters Patent and making part of the same.

To all whom it may concern:

Be it known that we, JOSEPH C. TONE and HENRY A. CLUM, both of the city of Rochester, in the county of Monroe, and State of New York, assignors to THEOBALD W. TONE, of the same place, have invented certain new and useful improvements in stamping and cancelling, or either separately, all kinds of commercial paper, such as notes, drafts, checks, and bills of exchange, also tickets, revenue and other stamps, &c.; and we do hereby declare that the following is a full and exact description thereof, reference being had to the accompanying drawings, making part of this specification, in which—

Figure 1 is a side elevation of our improved instrument.

Figure 2, an enlarged transverse vertical section.

Figure 3, an elevation of one of the wheels, with one of the guards partially broken away, to show the interior arrangement.

Figure 4, a plan of the printing and cancelling-table.

Figure 5, a sectional elevation of a portion of one of the box-wheels.

Figure 6, an elevation of one of the movable types.

Like letters of reference indicate corresponding parts in all the figures.

The object of this invention is to both print and cancel, or either separately, all kinds of commercial paper, tickets, stamps, &c., in the manner substantially as hereinafter described; also, to so combine and arrange type-wheels, as to adapt the same to a long-continued usage in indicating the year, month, and day, with as little difficulty and change as possible.

In the drawings—

A indicates the frame or stand, to which the operating parts are attached.

On its base *a*, we mount two vertical plates or standards *B B*, at suitable distance apart to receive the type-wheels between, as hereafter described.

On top of the vertical plates is situated the printing-table or bed *C*, which imparts the impression to the paper in stamping, the same being provided with suitable lettering for the purpose.

Horizontally through the plates *B*, passes a shaft, *E*, on which are mounted two box type-wheels *F F'*.

These wheels are made hollow, to hold type-wheels proper, *G G'*, which have an independent turning movement inside of the box-wheels.

The periphery of the wheels reaches through openings *e e* in the printing-table, and rests flush with the upper surface of the same.

One box-wheel, *F*, fig. 4, has raised upon its periphery, in type-characters, the names of the twelve months of the year in succession, forming the complete circle of the wheels.

The other box-wheel *F'* has also raised upon its periphery, in a corresponding manner, the first three fig-

ures of a series of decades of years—thus, 186, 187, 188, &c., the number of decades marked being twelve, corresponding in number with the twelve months marked on the month-wheel before described.

The inner type-wheels are, respectively, provided with radial slots *b b*, in which rest and slide movable types *c c c' c'*.

The lower ends of these types are rounded, as shown at *d*, to be acted on and elevated by wedge-shaped slides *f*, which are pressed under them, as shown in fig. 2.

The types are prevented from rising too high by pins or stops *g*, which strike under the edge of the guards *h* of the box-wheels. When thus elevated to their highest position, the characters marked on the types come just flush with those on the periphery of the box-wheels, so as to form the complement of the reading to indicate the year, month, and day.

In order that the heads of the types may pass through the box-wheels, openings or slots of proper size are made through the periphery of the latter, between the series of letters or numbers marked thereon.

The number of types employed in the type-wheel *G* is thirty-one, to correspond with the greatest number of days in a single month, and these are numbered 1, 2, 3, &c., upward, to 31, inclusive. This type-wheel, therefore, receives one revolution a month, to bring the numbers in successive use day after day; and the corresponding box-wheel *F* receives one revolution a year, to bring the series of characters on its periphery in successive use, to indicate the month.

The number of types in the type-wheel *G'* is ten, commencing with 1, and running to 90, inclusive. These, when brought successively in use, in connection with the series of numbers "186," "187," &c., on the box-wheel, indicate the current year. Thus the zero-character, when brought up, indicates the perfect decade "1870," "1880," &c., and the digits, when brought up, indicate the intermediate years "1871," "1872," &c. It is obvious, therefore, that the type-wheel *G'* receives one revolution in ten years, and the box-wheel *F'* one revolution in one hundred and twenty years.

The wedge-slides *f*, which raise the types, pass through slots formed in both box and type-wheels. In order to change the wheels, of course these slides must be withdrawn. That which passes through the year-wheels, owing to the infrequency of its removal, is made separate and detached, but that which passes through the month and day-wheels, from its frequency of withdrawal, is preferably jointed to a knob, *k*, which is hinged at *l*, so as to turn back.

A spring, *m*, bearing under the knob, holds the slide to its place.

A knob, *k'*, is also secured to the shaft *E* on the opposite side, by which the latter is turned, and consequently the type-wheels.

This connection is made by means of a pin, *n*, which passes transversely through the sleeve of the knob and the shaft itself. By withdrawing this pin, and inserting it longitudinally, as indicated by dotted lines in fig. 2, the action is changed from the daily to the yearly wheels, and when the change of the latter is accomplished, the pin may be returned to its former place.

The action of the wheels above described will be readily understood. The year, month, and day may be accurately indicated for a space of one hundred and twenty years.

We are aware that a single type-wheel has before been used, to adjust the day of the month, in stamps, but such is not the equivalent of our invention. We present a combination of type-wheels, which indicate not the day of the month alone, but the day, month, and year combined, and is capable of adjustment to do this for a comparatively unlimited time.

The printing-table or bed *C* may present any desired lettering for producing the stamping. In addition to other lettering, the word "cancelled" may be conveniently used, to call attention more particularly to the fact that paper or the stamp is cancelled.

In connection with the lettering of the table, we employ, for cancelling commercial paper, such as notes, drafts, bills, &c., also revenue-stamps, knives, punches, or other cutting-devices *p p*, which, at the moment of stamping, cut the paper through, and thus produce the mutilation necessary to legally cancel it. This is of the utmost importance in banks, as thereby a second handling of the paper is obviated, and fraud is prevented, by not allowing the uncancelled paper to pass through the hands of dishonest clerks or others.

As it is not desirable to cancel all paper at the time it is stamped, the cutters may be made removable by loosening a thumb-screw, or by other means.

If desirable, also, stamps may be made in manner before described, without using the cutters.

In ordinary hand-stamps, the printing-table or bed is attached to the stamping-rod that moves up and down.

In our invention this arrangement is reversed, the printing-bed being rigidly fixed below, while the platen *R* is attached to the stamping-rod *H*, and made to rise and fall with it.

The ribbon-cases *I I* are also attached to the lower end of the stamping-rod, and the inked ribbon *P*, passing from one to the other, is so situated over the printing-bed as to produce the impression on the paper beneath it as it is depressed. In ordinary use this ribbon may be of just such width as to cover the print of the type-table, and yet come between the cutters, so as not to be mutilated.

By reversing the position of the printing-bed and platen, as above described, the lettering on the latter does not have to be reversed to produce the proper impression, as is the case with other hand-stamps.

The stamp-rod *H* rests in a cylinder, *K*, which is adjustable up and down in the socket *L* of the frame. This cylinder is fixed in any desirable position by a setscrew, *s*, or equivalent. By this means it will be perceived the stroke of the stamp-rod may be changed to any length, the base of the cylinder serving as a stop to the top of the platen as it is carried back by spring *J*.

This is of importance in gauging the power of the stamp according to the work to be done. If several thicknesses of paper are to be cut, more power is required than where there is but one. By this adjustment the face of the printing-bed and the cutters is prevented from becoming injured.

To prevent blotting, we employ a dry ribbon, *M*, over or outside the inked ribbon *P*. This feature we also believe new.

We are aware that a type-wheel used in connection with a hand-stamp is old; therefore, we do not claim such broadly. We are aware, also, that a cancelling-cutter combined with a stamping-rod is old; neither do we broadly claim such; but

What we claim as our invention, and desire to secure by Letters Patent, is—

1. The combination, in a hand-stamp, of two type-wheels, one within the other, the outer having fixed lettering or numbering on its periphery, and the inner having movable types, which, when forced out, form, in conjunction with the outer, a complete indication of date, substantially as described.

2. The arrangement, with the jointed slide *f*, of the hinged knob *k*, substantially as described.

3. The arrangement, with the knob *k* and shaft *E*, of the movable pin *n*, operating in the manner and for the purpose specified.

4. The combination, with the stamp-rod *H*, of the adjusting-cylinder *K*, whereby the stroke of said rod is changed, substantially as described.

5. The combination of the dry ribbon *M* with the inked ribbon *P*, operating in the manner and for the purpose specified.

In witness whereof, we have hereunto signed our names, in the presence of two subscribing witnesses.

JOSEPH C. TONE.

HENRY A. CLUM.
